UNITED STATES PATENT OFFICE

2,455,300

RADIO TUBE SOCKET

Albert W. Franklin, New York, N. Y.

Application December 23, 1944, Serial No. 569,579

2 Claims. (Cl. 173—328)

1

This invention relates to improvements in radio tube sockets and socket terminal prong receiving clips therefor.

An object of this invention is to provide an extremely simple and inexpensive modification of vacuum tube prong receiving clips to facilitate grounding of the socket on the chassis of the equipment of which it is to be a part.

Another object of the invention is to provide a novel construction by means of which the terminal clip in which the screen grid terminal prong socket is received is shielded and/or grounded.

Other and more detailed objects of the invention will be apparent from the following disclosure of the several embodiments thereof illustrated in the drawings.

This invention resides substantially in the combination, construction, arrangement and relative location of parts, all as will be described in detail below.

In the accompanying drawings,

Figure 1 is a perspective view of a radio tube socket mounted on a support and embodying the grounding feature of this invention;

Figure 2 is a perspective view of the terminal clip modified for grounding;

Figure 3 is a cross-sectional view taken on the line 3—3 of Figure 1;

Figure 4 is a plan view of the structure by means of which the shield for the screen grid terminal clip of a radio tube socket is shielded from adjacent clips and grounded;

Figure 5 is a perspective view of the shielding structure;

Figure 6 is a plan view of the stamping from which the shield is made;

Figure 7 is a cross-sectional view taken on the line 7—7 of Figure 4;

Figure 8 is a plan view of the stamping of a modified shield arranged for grounding independently of the clip to which it is attached;

Figure 9 is an elevational view of this modification as applied to a radio tube socket; and

Figure 10 is a detailed cross-sectional view taken approximately on the line 10—10 of Figure 8.

As is well known, it is common to provide some means for grounding at least one of the prong receiving clips of a radio tube socket. In the most common form this grounding means comprises a separate wire which is individually soldered to the prong receiving clip to be grounded, and in turn soldered to some adjacent portion of the metal chassis which supports the socket.

2

The construction illustrated in Figures 1 to 3, inclusive, provides an integral grounding tab forming part of the prong receiving clip to be grounded, by means of which a ground connection to the chassis may be quickly made by means of a single soldered connection through the agency of that tab. As illustrated in these figures, a portion of the metal chassis is indicated at 10, upon the underside of which the socket may be attached in accordance with usual practice by means of rivets through the openings 20. As illustrated, the socket includes a pair of superposed plates 11 and 12 of insulating material secured together by means of the riveted eyelets 19. A plurality of prong receiving terminal clips 13 are mounted on this base. As illustrated, they are all the same with the exception of the clip which has been indicated by the reference numeral 14 and shown in greater detail in Figure 2. This clip comprises a longitudinally slotted tubular portion 15 integral with a uniting web 16 and the right angled soldering lug or terminal 17. These clips are secured in the socket by passing the portions 15 and 17 through suitably shaped openings in the insulating plate 11, so that the connecting web portion 16 is clamped between the insulating plates 11 and 12. These features are of usual construction in this art.

The clip to be grounded differs from those just described by striking out of the soldering lug 16 a tab 18 which lies in the plane of the web 16, and thus extends exteriorly of the superposed insulating plates 11 and 12, as is clear from Figures 1 and 2. The extending end of the tab 18 is bent downwardly into contact with the adjacent portion of the chassis 10 and soldered thereto, as indicated in Figure 3. Thus the prong receiving clip to be grounded is quickly and easily grounded to the chassis by means of a single soldered connection at the tab 18 which, being integral with the clip, insures that the right clip is grounded.

The principles of this invention have been carried forward into the modifications illustrated in Figures 4 and 10, inclusive. One of these modifications is illustrated in Figures 4 to 7, inclusive. A chassis portion 10 is illustrated as before, and the socket is generally similar in construction to that previously described. In this case the screws or rivets 20 are shown for attaching the socket to the underside of the chassis. The prong receiving clips 13 are the same as before, and in this case a clip 14 like that shown in Figure 2 is employed and grounded by means of its tab 18, as in the previous case. The feature of this con-

struction is the grounded shield by means of which the prong receiving clip 13' is electromagnetically and electrostatically shielded from the other clips by means of a metal shield 21. The clip 13' is the one which normally receives the prong of the tube connected to the screen grid of the tube. The shield 21 is shown in Figure 6. It has an aperture 22 punched therein and a T-shaped incision 23 cut therethrough, as shown. It is provided with a short ear 25 and is bent up into the form clearly illustrated in Figures 4 and 5. The T-shaped slit 23 provides for the ears 26 and the aperture 22 permits riveting of the shield to the grounded clip 14 by means of the rivet 21, see Figure 4. The ears 26 engage the adjacent face of the socket plate 11 to impart transverse rigidity to the shield. The lug projects into a suitably positioned rectangular slot in the insulating plate 11, so as to anchor the free end of the shield 21 in a manner which will be obvious.

It will be seen from this description that the shield 21 electrically isolates the clip 13' from the other clips and the shield is simultaneously grounded by reason of its riveted attachment to the grounded clip 14, which clip is the same as that previously described.

In the modification of Figures 8 and 9 the only difference is that in this socket all of the clips 13 are the same, that is no clip like that of Figure 2 is used. In this case the shield 21 only differs from the shield of Figure 6 in that it is made long enough so as to project over the edge of the socket plate 11 and the downwardly extending tab 29 has its terminal end bent over at right angles into contact with the chassis 10 and is soldered thereto so that the shield is anchored at this end and grounded. The shield 21 being riveted to the clip 14' also grounds it. The clip 13' is, of course, shielded by it, as in the previous case. The ear 25 is provided for seating in a slit in the insulating plate 11, as in the previous case, so as to anchor the shield and prevent bending of it prior to the mounting of the shield on the chassis. Of course, the soldered tab 29 also serves its purpose, but is ineffective until the socket is put into use, and so it is preferable to provide the ear 25 by protecting the shield against damage prior to putting the socket into use.

From the above description it will be apparent

to those skilled in the art that the subject matter of this invention is capable of some variation as indicated in part by the modifications herein disclosed. I do not, therefore, desire to be limited to this disclosure, except as required by the appended claims.

What is claimed is:

1. A radio tube socket of the type described comprising a pair of insulating plates secured together in superposed relation, a plurality of terminal clips comprising spaced parallel portions one tubular shaped and the other in the form of a strip, said portions being connected by a web lying between said insulating plates and the strip portion of at least one of said clips having a struck out grounding tab integral therewith extending exteriorly of the plates in the plane of the web thereof.

2. A radio structure of the type described, a tube socket comprising an insulating support, and a plurality of prong receiving clips mounted on said support, a shield surrounding one of said clips and conductively connected to an adjacent clip, said shield having an integral grounding tab, and a conducting support to which said socket is attached and said grounding tab is conductively anchored.

ALBERT W. FRANKLIN.
